CLAIM

We claim the ornamental design for a wearable temperature therapy device, as shown and described.

DESCRIPTION

FIG. 1 is an isometric view from the top, front, right of the wearable temperature therapy device.

FIG. 2 is an isometric view from the bottom, back, left of the wearable temperature therapy device.

FIG. 3 is a plan view from the top of the wearable temperature therapy device.

FIG. 4 is a plan view from the bottom of the wearable temperature therapy device.

FIG. 5 is an elevation view from the left of the wearable temperature therapy device.

FIG. 6 is an elevation view from the right of the wearable temperature therapy device.

FIG. 7 is an elevation view from the back of the wearable temperature therapy device; and,

FIG. 8 is an elevation view from the front of the wearable temperature therapy device.

The broken lines shown in FIGS. 1, 3, and 5-8 illustrate portions of the wearable temperature therapy device that form no part of the claimed design.

1 Claim, 7 Drawing Sheets
